Patented Apr. 7, 1914.

UNITED STATES PATENT OFFICE.

FRANK D. BRYAN, OF MIDDLETOWN, PENNSYLVANIA.

REFILLABLE FUSE.

1,092,333.

Specification of Letters Patent.

Patented Apr. 7, 1914.

Application filed August 27, 1913. Serial No. 786,999.

To all whom it may concern:

Be it known that I, FRANK D. BRYAN, a citizen of the United States, residing at Middletown, in the county of Dauphin, State 5 of Pennsylvania, have invented certain new and useful Improvements in Refillable Fuses; and I do hereby declare the following to be a full, clear, and exact description of the invention, such as will enable others 10 skilled in the art to which it appertains to make and use the same.

This invention relates to improvements in electrical fuses.

The principal object of the invention is to 15 provide a simple device of this character wherein the fuse strips can be replaced.

Other objects reside in the peculiar construction and arrangement of the various parts of the fuse holder.

20 In the drawings: Figure 1 is an elevation of my fuse holder. Fig. 2 is an end view. Fig. 3 is a vertical longitudinal sectional view on the line 3—3 of Fig. 1. Fig. 4 is a transverse sectional view on the line 4—4 of 25 Fig. 1, looking in the direction of the arrows. Fig. 5 is an end view of the device with the end cap removed. Fig. 6 is a perspective view of one of the end sleeves.

Referring particularly to the accompanying 30 drawings, 10 represents a hollow open ended tube of insulated material at each end of which are formed diametrically opposite threaded holes 11. Embracing each end of the tube is a sleeve 12, this sleeve carrying a 35 pair of screws 13 for engagement in the openings 11 to hold the sleeve to the tube. The sleeve is bent on itself at the outer end as indicated at 14. At two diametrically opposite points, the doubled end is extended 40 inwardly as indicated at 15 to form ears. Each of these ears is formed with a threaded opening 16. A disk 17 is disposed within the doubled end of the sleeve and has at two diametrically opposite points the lugs 18 45 which fit within the spaces of the doubled portion. The fuses 19 have their opposite ends bent at right angles and bifurcated as indicated at 20, these ends being engaged on the ears 15 and straddling the screws 21 50 carried by the disk 17. These screws are en-

gaged through the before mentioned openings 16 and tightly clamp the bifurcated ends of the fuses between the ears 15 and the disk 17. In the central portion of each of the disks 17 is formed a slot 22 within 55 which is soldered or otherwise secured an attaching ear 23. One of these ears 23 has a slot opening through the end thereof, while the other one has a slot opening through the side. These ears 23 are for engagement 60 with the usual binding screws, as will be readily understood. In the central portion of each of the fuses 19 is formed a transverse opening 24 which insures the separation of the fuse at the center when the same 65 burns out.

The description of one end of the fuse holder will serve for the other end, as the parts at the other end are identical in construction with the end described, with the 70 exception of the ears 23, which have already been distinguished.

It will of course be understood that the interior of the tube is filled with some fire-proof material as asbestos or the like as is 75 the custom with devices of this class.

From the foregoing, it will readily be seen that I have provided a simple and cheap device of this character and one in which the fuse may be quickly and easily replaced 80 when burnt out. It will be understood that by loosening the screws 21 and removing the disks 17, that the fuse strips 19 may be quickly withdrawn, as there will be no obstruction or lateral projection on the inner 85 broken ends of the strips to prevent easy withdrawal thereof.

What is claimed is:

In a fuse holder, an insulated tube, a sleeve detachably secured on each end of 90 the tube and embracing said tube, the outer end portion of each of the sleeves projecting beyond the end of the tube and having portions arranged at diametrically opposite points bent inwardly and transversely to 95 form ears which engage the ends of the tube, said bent portions leaving diametrically opposite openings in the projecting portions of the sleeves, fuse strips having openings formed centrally therethrough approxi- 100

mately midway of their lengths, right angularly turned bifurcated end portions engaged on the ears of the sleeves, disks disposed within the projecting ends of the sleeves and provided with diametrically opposite radial lugs fitted within the openings of the sleeve, said disks resting on the lateral turned ends of the fuse strips, and screws carried by the disks engaging through the

bifurcated ends of the fuse strips and through the ears of the sleeves.

In testimony whereof, I affix my signature, in the presence of two witnesses.

FRANK D. BRYAN.
